UNITED STATES PATENT OFFICE

164,412

TICKET DISPENSER

John W. Edgemon, Jr., Los Altos, and Ellsworth W. Carroll, Redwood City, Calif., assignors to Catz and Weir, San Francisco, Calif., a copartnership

Application March 6, 1950, Serial No. 8,363

Term of patent 3½ years

(Cl. D52—3)

To all whom it may concern:

Be it known that we, John W. Edgemon, Jr., and Ellsworth W. Carroll, citizens of the United States, residing respectively in the city of Los Altos, county of Santa Clara, State of California, and city of Redwood City, county of San Mateo, State of California, have invented a new, original, and ornamental Design for Ticket Dispenser, of which the following is a specification, reference being had to the accompanying drawing, forming part thereof.

Figure 1 is an isometric front view of the ticket dispenser, showing our new design;

Figure 2 is an isometric rear view of the ticket dispenser.

The essential features of the design reside in the solid portion.

We claim:

The ornamental design for a ticket dispenser, as shown and described.

JOHN W. EDGEMON, JR.
ELLSWORTH W. CARROLL.
